(57) **CLAIM**

The ornamental design for a cooler, as shown and described.

DESCRIPTION

FIG. 1 is a front perspective view of a cooler, showing our new design, shown in a closed position;

FIG. 2 is a back perspective view thereof;

FIG. 3 is a front elevation view thereof;

FIG. 4 is a back elevation view thereof;

FIG. 5 is a left view thereof, the right side being a mirror image to the left side;

FIG. 6 is a top plan view thereof;

FIG. 7 is a bottom plan view thereof;

FIG. 8 is a front perspective view of a cooler, showing our new design, shown in an open position;

FIG. 9 is a back perspective view thereof;

FIG. 10 is a front elevation view thereof;

FIG. 11 is a back elevation view thereof;

FIG. 12 is a left view thereof, the right side being a mirror image to the left side;

FIG. 13 is a top plan view thereof; and,

FIG. 14 is a bottom plan view thereof.

In the drawings, the broken lines illustrate portions of the cooler that form no part of the claimed design.
